ADJUSTABLE CATCH BASIN

Ernest E. Ward, Harrison, Maine

Application April 4, 1939, Serial No. 266,028

1 Claim. (Cl. 182—2)

The invention relates to a catch basin and more especially to drop inlets used on highways to collect or gather water.

The primary object of the invention is the provision of a device of this character wherein the same involves upper and lower sections, the upper section being adjustable relative to the lower section and is attached to the latter in a novel manner, and in this way the device can be set in a road bed for final grading or surfacing of the roadway, the height of the device being regulated in accordance therewith.

Another object of the invention is the provision of a device of this character wherein its body construction is such that it can be lengthened or shortened according to the lay of the road bed, the body being sectional and these telescopically interfitted with each other and adjustable one with respect to the other, the device being usable to receive water from the sides or other areas of the road when installed therein and have the water collected and run off through a pipe avoiding the presence of water pools or surface accumulation of the water thereof.

A further object of the invention is the provision of a device of this character which is simple in its construction, thoroughly reliable and efficient in operation, possessed of few parts, being strong, durable and inexpensive to manufacture and install.

With these and other objects in view the invention consists in the features of construction, combination and arrangement of parts as will be hereinafter more fully described in detail, illustrated in the accompanying drawing which discloses the preferred embodiment of the invention and pointed out in the claim hereunto appended.

In the accompanying drawing:

Figure 1 is an elevation partly broken away of a device construction in accordance with the invention.

Figure 2 is a view similar to Figure 1 looking substantially at right angles thereto.

Figure 3 is a top plan view.

Figure 4 is a perspective view of a fastener for the device.

Figure 5 is one of the tie bolts of the fastener.

Similar reference characters indicate corresponding parts throughout the several views in the drawing.

Referring to the drawing in detail A designates generally the basin or drop inlet constructed in accordance with the invention and 55 in this instance comprises cylindrical lower and

upper sections 10 and 11, respectively, the upper section being of cross sectional diameter slightly greater than the cross sectional diameter of the lower section 10 so that the said upper section can be telescoped over the said lower section in 5 the setting-up of the device. The sections 10 and 11 are made from sheet steel or other desired metal and both are corrugated at 12.

The section 11 is longitudinally slotted for spreading and contraction thereof, and at the 10 slit denoted at 13 the edges next thereto are disposed partially in overlapped relation to each other as at 14, and partially united by suitable fasteners 15 so that in this manner one end will be permanent against spreading, while the other 15 end and a portion inwardly of the section 11 can be spread or contracted with the result that the telescopic fitting of the section 11 over the section 10 can be conveniently had. Also this character of fitting enables adjustment of the upper 20 section relative to the lower section.

The lower open end of the section 10 is closed by a cementitious slab and bottom 16 being fitted in the lowermost corrugation 12 therein, while the uppermost open end of the section 11 25 has fitted therein a grate cover 17, being lipped peripherally at 18 for seating engagement at the top edge of the device as will be clearly apparent in Figure 1 of the drawing.

Seamed or welded to the section 10 is a lateral 30 corrugated pipe 19 constituting the side outlet from the device for the delivery of water therefrom. The water from the road bed is let into the device through the cover 17, being shown in detail in Figure 3 of the drawing.

Secured to the section 11 on opposite sides of the edges and next to the slit 13 and contiguous to the lowermost end of this section are angle pieces or L-brackets 20, these being coupled by adjustable fasteners 21 so that the section 11 40 can be contracted or spread and in contracting the same will be firmly clamped telescoped over the section 10. The corrugations 12 of these sections 10 and 11 interfit each other in their clamped relation to each other.

The device in the installing thereof is sunk in the road bed so that through adjustment thereof the cover 17 will be flush, or approximately so, with the surface of said road bed. The upper section 11 can be adjusted within a 50 reasonable ratio to take care of various heights of fill capacity of the device when sunken in the road bed.

What is claimed is:

A device of the character described comprising 55

corrugated cylindrical sections adjustably inter-fitted with each other and having their corrugations engaged one with the other, one section being slit from end to end, the edges of the slit being diagonally across with respect to each other for presenting increasing and decreasing overlap and gap, respectively, between the ends with one end having a fixed side and the other end being

enlarged or decreased in size, means adjustably connecting the edges of the slit next to the increasing or decreasing end thereof, a grate, a ring in the fixed end and accommodating the said grate, and a solid bottom and side extension 5 nipple, respectively, on the other section.
